UNITED STATES PATENT OFFICE

JOSEPH W. BISHOP, OF MUSKEGON HEIGHTS, MICHIGAN, ASSIGNOR TO THE BRUNS-WICK-BALKE-COLLENDER COMPANY, OF CHICAGO, ILLINOIS, A CORPORATION OF DELAWARE

FLOOR SURFACING MACHINE

Application filed February 11, 1927. Serial No. 167,451.

My invention relates to the maintenance of floors and the like, especially of the type used for bowling alleys, dance halls, etc. The object of the invention is to provide an improved surfacing machine for such floors.

In the accompanying drawings,

Figure 1 is a side elevation of a floor surfacing machine;

Figure 2 is a front elevation of the same;

Figure 3 is a sectional view on the line 3—3 of Figure 1;

Figure 4 is a section through the fan mounting;

Figures 5 and 6 are a front and an end elevation of the abrading roll; and

Figure 7 is a section on line 7—7 of Figure 5.

In the embodiment of the invention selected for illustration, the body of the machine comprises a box frame 10 open at the front and bottom and supported in its movement over the floor by main wheels 12 housed inside the box and rotatable on a transverse axis in front of the center of gravity. The frame is strengthened in the plane of the main wheels by a rib 14 forming a cross brace. A three point support is completed by the caster wheel 16 mounted on the lower side of a plate 18 projecting back from the rear of the frame.

The main parts of the machine are the abrading roll 20 located in front of the open front end of the machine; the exhaust fan 22 housed inside the frame near the rear, and the exhaust passageways associated with said fan; the control column indicated as a whole by the reference character 26 and extending upwardly and rearwardly from the rear end of the frame; and the power source indicated as an electric motor 28. The frame is provided with an integral inclined socket 30 for receiving and supporting the control column, and the socket 30 and plate 18 are braced and strengthened by an integral rib 32 extending across between them.

The abrading roll

Referring now to Figures 5 and 6, the abrading roll comprises a sheet metal cylinder 34 having a head 36 at each end. Each

head carries a central boss 38 for receiving the drive shaft, an enlargement at 40 for holding the gripping rods 42, and a dummy enlargement 44 functioning as a simple weight to counterbalance the mass of the gripping rods 42 and enlargement 40.

Each gripping rod 42 comprises a main knurled portion, a smooth end portion 46 having an annular groove to receive a retaining set screw 48, and a smooth end portion 50 terminating in a squared head 52. The holding rods are set at a slight angle with respect to the axis of the roll, and a slot is cut at 54 through the cylinder 34 and radially into both heads 36 between the holding rods. Each knurled portion is flattened as at 56 (Fig. 7).

To prepare the roll for use, a flexible sheet 58 carrying abrasive material is wrapped around the cylinder 34 and its edges are slipped between the knurled portions of the holding rods while these are positioned with their flattened portions 56 facing each other. By rotating the rods to the position shown in Figure 7, the edges of the flexible sheet 58 may now be drawn in snugly and the roll is ready for use.

The roll mounting

A transverse shaft 60 is mounted in the frame at the front near the top. Arms 62 pivoted on the shaft 60 extend outward and downward at opposite sides to support bearings at 64 for the ends of the roll shaft 66. Beyond the bearings the arms are continued in the form of extensions 68 projecting forwardly beyond the roll 20 and terminating in bumpers 70 to prevent movement of the roll against a wall or other vertical surface. The arms 62 are interconnected by sleeves 72 integral therewith and extending in to the center of the machine. At the center these arms are interconnected by means of short levers 74 and a cross bolt 76 interconnecting the ends of the levers. This bolt is threaded into the end of one lever and the other lever has a slotted opening to receive the bolt. The bolt is readily accessible so that minor adjustments to keep the shaft 66 in any desired alignment relative to the level of the floor

supporting the wheels 12 can readily be made at any time.

The roll control

- 6 Means are provided for lifting the roll out of contact with the floor surface and for holding it resiliently against the floor surface when desired. I have illustrated a control handle 78 shown in Figure 1 in the position 10 for permitting the roll to engage the floor, and rotatable in a clockwise direction through approximately 90° about the horizontal handle 80 by which the operator moves the machine from place to place. This handle 80 is rigidly mounted in a U-shaped bracket 83 having a split socket 85 threaded on the upper end of the main tube 84 and clamped in place by a tightening bolt 87. The transmission from the handle 78 to the 15 pivoted yoke made up of the arms 62 and sleeves 72 comprises a cam sector 81 carried by the handle 78 and bearing against the end of the push rod 82, which push rod extends axially down the center of the main tube 84 of the control column. The lower end of the 20 push rod 82 operates the horizontal arm 86 of an intermediate bell crank lever having a downwardly projecting arm 88 connected by a horizontal link 90 with a crank arm 92 integral with one of the sleeves 72. Thus the 25 downward thrust on the rod 82 rotates the bell crank lever 86, 88 and the yoke in a clockwise direction and lifts the roll off the floor. When in the position of Fig. 1, it also 30 functions as a positive stop, limiting the downward movement of the roll.
- The resilient means for pressing the roll against the floor comprises a coil spring 94 housed in a tubular socket 96 opening rearwardly through the rear wall of the frame. The spring encircles a tension rod 98 connected to the downwardly extending arm 88 of the intermediate bell crank lever, and bears against a thrust collar 100 held in place 40 by an adjustment nut 102 threaded on the rear end of the rod 98. By providing the collar 100 and nut 102 with interengaging irregularities of contour indicated at 104, the nut 102 may be held in adjusted position and 45 prevented from unscrewing on account of vibration or any other cause.

Exhaust

- 55 The open mouth 106 of the exhaust system lies just back of the lower portion of the roll 20 to receive the dust and particles formed by the action of the roll. The passageway tapers rapidly to a connection with an intermediate connecting tube 108 leading 60 to the intake tube 110 of the fan casing. The fan may be of any approved design. It is illustrated as comprising a rotor 112 supported on a shaft 114 mounted in suitable ball bearings in a boss 116 cast on the wall of the 65 frame. The outer end of the shaft carries a

pulley 118 by means of which the fan is to be rotated. The tangential outlet 120 is curved upwardly at 122 and enters a connecting ring 124 over which the mouth of the dust bag 126 is held by the retaining device 128. The upper end of the dust bag may be held in place by a coil spring 130 running to the top of the control column.

The motor

75 Transverse rails 132 are mounted on top of the frame and held in place by bolts 134 passing through fore and aft slots in the top of the frame. The motor rests on these rails and is held down by bolts 136 entering transverse slots 138 in the rails. Thus the motor can be adjusted both longitudinally and transversely. The power leads to the motor come in at 140 and pass through the control box 142 provided with a control switch 144 and safety fuse means 146. From there they pass down a protecting tube 148 to the lower junction box 150 from which they go direct to the motor. The box 142 is clamped on the main tube 84 by suitable clips 152. At the 80 bottom the tube 84 is fastened in the socket 30 by a U-bolt 154 and also by fastening the box 150 direct to the upper end of the bracket by ordinary bolts.

Transmission

95 The motor shaft carries a pinion 156 connected by a chain 158 to the sprocket 160 for driving the roll 20. Beyond the pinion 156 it also carries a pulley 162 for a belt connection with the pulley 118 to drive the fan. The axis of the motor shaft is in substantially the same plane as the shafts 64 and 60 when the wheel is operating. Thus the movement of the abrading roll up out of engagement with the floor has a negligible effect on the tightness of the chain 158. This tightness can be adjusted by longitudinal movement of the motor with very little effect on the tightness of the belt for driving the fan, 100 since the belt extends almost directly down while the chain extends downward and forward at an angle of about 45°.

105 I have provided shields to cover the transmission comprising a belt shield 164 extending over the top of both the pulley 162 and the pinion 156 and a side apron 166 fastened to the belt shield at 168. Both shields are supported by a bracket 170 and bolt 172.

110 Without further elaboration, the foregoing will so fully explain the invention that others may, by applying current knowledge, readily adapt the same for use under various conditions of service. It will, for instance, be obvious that it is not essential that all the elements described be employed in conjunction, 115 as they may advantageously be utilized in various combinations and subcombinations.

120 What I claim is:—

- 125 1. A floor surfacing machine comprising a

box frame, open at the front and bottom; a column extending upwardly and rearwardly from the rear end of said frame; a yoke journaled on a transverse axis in said frame and having arms extending forward and downward; an abrading roll journaled on a transverse axis on the ends of said arms; an exhaust fan inside said frame near the rear at one side; a collector having a large receiving mouth just behind the lower portion of said roll and leading to said fan; a duct leading out of said fan; a receiving bag suspended below said column and connected to said duct; a handle at the top of said column for moving the entire machine over the floor; a second handle at the top of said column; a linkage extending entirely inside said column and frame for raising and lowering said roll by means of said second handle; tension means 20 adjustable at the rear of said frame and acting on said linkage to press said roll toward the floor; a motor on top of said frame and adjustable both transversely and longitudinally thereon; chain and sprocket connections running from said motor downward and forward outside said frame at one side for driving said roll; belt and pulley connections running from said motor downward outside said frame at the same side for driving said 25 fan; shields carried by said frame for covering said connections; switch means at the top of said column for controlling said motor; conductors from said switch means to said motor; and rigid housing means forming part 30 of said column and enclosing said conductors.

2. A floor surfacing machine comprising a box frame, open at the front and bottom; a column extending upwardly and rearwardly from the rear end of said frame; a yoke journaled on a transverse axis in said frame and having arms extending forward and downward; an abrading roll journaled on a transverse axis on the ends of said arms; said yoke having means for relative angular adjustment 40 of its arms about their common axis; a handle at the top of said column for moving the entire machine over the floor; a second handle at the top of said column; a linkage extending entirely inside said column and frame for 45 raising and lowering said roll by means of said second handle; tension means adjustable at the rear of said frame and acting on said linkage to press said roll toward the floor; a motor on top of said frame and adjustable both transversely and longitudinally thereon; connections running from said motor downward outside said frame at one side for driving said roll; and a shield carried by said 50 frame for covering said connections.

JOSEPH W. BISHOP.
